UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

UNIFORMLY TENSIONED REVERSING MOTION FOR LOOM LET-OFFS.

Application filed August 22, 1925. Serial No. 51,841.

This invention relates to improvements in let-off motions for looms and more particularly to means for letting back the fabric and warps at the time of a pick out.

5 When it is desired to remove a mispick from the fabric the weaving processes are reversed and all picks laid after the mispick occurred are removed. This leaves the fell of the cloth somewhat in advance of the reed 10 when the latter is on front center and it is necessary that the cloth and warps be moved backwardly to place the fell in proper position. Unless considerable care is exercised with the usual let-off this latter operation 15 will place too great or too little tension on the warps and a mark will be left in the cloth on the first pick woven after the pick out.

It is the general object of my present invention to provide means for turning the cloth and warps back in the loom in such a way as to leave the warps under the same tension which existed before the pick out.

It is a further object of my invention to 25 provide normally taut friction devices to resist the advance of the warp so arranged that they can be released at the time of pick out to assume a new angular relation after which the original tension can be restored 30 and the parts then moved back to normal position to give the warp a reverse movement under the same tension which prevails during normal weaving.

In my co-pending application, Serial No. 35 46,282 I have shown a somewhat similar mechanism wherein the adjustable hand lever is used first to create slack in the friction band by a downward movement and then to tighten said band by an upward 40 movement when the hand lever is restored to normal position, the upward movement being accompanied by a reverse movement of the warp. The devices set forth in said application do not insure that the warp shall 45 always be under the normal weaving tension and it is the particular object of this present invention to establish normal weaving tension before the hand lever is started on its return movement to normal position. 50 This object is attained by the use of a normally stationary mounting for the hand lever and friction band which can be moved as a whole to give the friction band an angular

movement with respect to the friction surface cooperating therewith, the hand lever and mounting being connected together in the same relative positions they ordinarily occupy before being returned to normal position.

With these and other objects in view which will appear as the description proceeds my invention resides in the combination and arrangement of parts hereinafter described and set forth in the claims.

In the accompanying drawings wherein I have shown one embodiment of my invention,

Fig. 1 is a vertical transverse section through a loom looking toward the side of the loom equipped with my invention,

Fig. 2 is a view similar to Fig. 1 but showing the parts in a different position,

Fig. 3 is a fragmentary view showing certain of the parts shown in Fig. 1 in the position they assume when a reverse stroke is about to begin.

Fig. 4 is a fragmentary top plan view of the hand lever and parts associated therewith taken in the direction of arrow 4, Fig. 1, and

Fig. 5 is a vertical section on line 5—5 of Fig. 1.

My invention may be used in connection either with a warp beam or with a drum such as is customarily used with a creel but I have chosen to illustrate my invention as applied to the latter type of loom. Referring more particularly to the drawings it will be seen that I have provided a loom frame 10 having mounted for rotation at the rear thereof a warp delivery drum 11 which receives the warp W from the creel (not shown) at the rear of the loom and passes the same forwardly to the harnesses (not shown). Secured to and moving with the drum is a large gear 12 which meshes with a pinion 13 secured to a cross shaft 14. Rigid with respect to said pinion 13 is a friction drum 15 around a portion of which extends a flexible friction band 16 having one end secured to a normally fixed stud 17 and the other end secured to a stud 18 movable with respect to the stud 17 to adjust the tension of the band and vary the friction between the same and the drum 15. Said stud 17 is carried by a relatively long lever 19

loosely mounted on the cross shaft 14 and having pivoted thereto as at 20 a hand lever 21 which supports stud 18.

Under normal conditions the lever 19 is held stationary by a weighted lock 22 pivoted at 23 to a bracket 24 secured to the loom frame 10 as shown in Figs. 1 and 5. Said weighted lock 22 has a detent 25 which normally rests under the lever 19 to limit downward movement of the latter while a fixed stud 26 secured to the loom frame engages the upper portion of the lever 19 to limit upward movement thereof.

Said lever 19 is formed with upper and lower spaced arms 27 and 28, respectively, between which extends an adjusting screw 29 actuatable by a hand wheel 30. Said wheel is secured to the screw 29 above the arm 27 and a collar 31 is secured to said screw on the under side of said arm 27, this construction permitting free rotation of the screw 29 in its bearing but preventing longitudinal movement thereof. A block 32 is threaded on the screw 29 and is provided with a detent or notch 33 which normally receives the forward end of the hand lever 21. Rotation of hand wheel 30 moves said block up or down to adjust the position of the hand lever 21 with respect to the lever 19 and therefore the friction between the band 16 and the drum 15.

Under normal conditions lever 19 is held stationary by means already described so that the hand lever 21 may be moved with respect thereto. At the time of pick out said lever 21 will be flexed off the notch 33 as shown in dotted lines in Figs. 4 and 5 and lowered by the operator to the position shown in full lines in Fig. 2. As said hand lever is lowered it will engage the inclined face 34 of the weighted lock 22 and will move the same to the dotted line position shown in Fig. 5. This releases the lever 19 and the weaver can prevent the same from falling by holding hand wheel 30. The parts are now moved to the dotted line position shown in Fig. 2, the relative movement of the hand lever 21 with respect to the lever 19 having slackened the band 16 so that said parts may move downwardly without causing rotation of the drum 15. The operator will then hold the lever 19 in lowered position and will raise the hand lever 21 until the same is resting on the block 32. The friction band is thus restored to its original tension and as the levers 19 and 21 are raised the drum will be given an angular movement in a direction to turn the drum 11 backward. This operation may be repeated as often as desired until the fell of the cloth has reached the reed which is on front center. Additional movement of levers 19 and 21 after the fell has reached the reed causes slipping of the band around the drum to restore the same tension which

existed before the pick out. A lower stop 35 secured to the loom frame limits downward movement of the lever 19 but the hand lever 21 is free to pass by said stop as indicated in dotted lines in Fig. 2.

From the foregoing it will be seen that I have provided means for moving the friction band as a whole about the drum 15 so that the same is slackened to assume a different angular position with respect to said drum. The original tension may then be restored while the operating levers are in lowered position after which said levers may be raised to transmit motion to the warp delivery drum by a frictional force which is the same as that which exists under normal weaving conditions.

Having thus described my invention it will be apparent that changes and modifications may be made therein by those skilled in the art without departing from the spirit and scope of the invention, and I do not wish to be limited to the details herein disclosed, but what I claim is:

1. In a let-back mechanism for looms having a warp delivery means and a friction surface operatively connected with the means, a flexible friction element to cooperate with the friction surface and tending normally to retard movement of the warp delivery means, a normally stationary member connected to one end of the flexible element, a second normally stationary member positively held against movement under normal conditions of the loom mounted on and movable with respect to the first member when the warp is to be let back and connected to the other end of the flexible element, and means to hold the members in normal relative position in all positions of the first named member.

2. In a let-back mechanism for looms having a warp delivery means and a friction surface operatively connected to the means, a flexible friction element to cooperate with the friction surface and retard the movement of the warp delivery means, a two-part supporting means for the friction element normally stationary when the loom is running, said parts being movable with respect to each other to slacken the flexible element when the warp is to be let back and freely movable together to an abnormal position while the element is slack to move the flexible element as a whole with respect to said friction surface, and means to hold the parts in normal relative position while said parts are being moved together from abnormal toward normal stationary position to maintain normal friction between the element and friction surface.

3. In a let-back mechanism for looms having a warp delivery means and a friction surface operatively connected to said means, a flexible friction element to cooperate with

- the friction surface to retard movement of the warp delivery means, a pair of connected members one of which is secured to one end of the flexible member and the other of which is secured to the other end of the flexible member, said members being normally stationary and normally held against movement during normal running of the loom but movable relatively to each other to slacken the flexible element and movable together to move said element as a whole with respect to the friction surface to an abnormal position, and means to maintain said members in normal relative position while they are being moved together from abnormal toward normal stationary position to maintain normal friction between the element and friction surface.
4. In a let-back mechanism for looms having a warp delivery means and a friction surface operatively connected to said means, a flexible friction element to cooperate with the friction surface to retard movement of the warp delivery means, a pair of connected members one of which is secured to one end of the flexible member and the other of which is secured to the other end of the flexible member, mechanism to hold said members normally stationary against movement and adjustable to vary the relative position of the members, said members being movable relatively to each other independently of the mechanism to an abnormal position to slacken the flexible element and movable together while in abnormal position to move said element as a whole with respect to the friction surface to an abnormal position, and means to maintain said members in normal relative position while they are being moved together from abnormal toward normal stationary position to maintain normal friction between the element and friction surface.
5. In a let-back mechanism for looms having a warp delivery means and a friction surface operatively connected to the means, a flexible friction element cooperating with the friction surface to retard movement of the warp delivery means, a pair of members connected together each being connected to one end of the flexible element, adjustable means carried by one of said members and engaging the other member to vary the relative position of said members and the tension of the flexible friction element, a support to hold said members normally in stationary position, said members being movable relatively to each other to an abnormal relative position to slacken the friction element and movable together freely while in abnormal relative position to move said element as a whole with respect to the friction
- surface to abnormal position, and means to maintain said members in normal relative position while said members are being returned from abnormal to normal stationary position to maintain normal friction between the element and friction surface.
6. In a let-back mechanism for looms having a warp delivery means and a substantially cylindrical friction surface operatively connected to said warp delivery means, a flexible friction element cooperating with the friction surface to retard movement of the warp delivery means, a pair of members connected together and movable concentrically with respect to the cylindrical surface, one of said members being connected to one end of the flexible friction element and the other member being connected to the other end of the element, said members being movable relatively to each other to slacken the flexible friction element and movable together from normal stationary position about the center of the cylindrical friction surface to move the element as a whole with respect to said friction surface, said members being returnable to normal relative position with respect to each other when spaced from their normal stationary position to reestablish the original tension of the friction element, and means to maintain said members in normal relative position while being moved toward normal stationary position.
7. In a let-back mechanism for looms having a warp delivery means and a substantially cylindrical friction surface operatively connected to said warp delivery means, a flexible friction element cooperating with the cylindrical surface to retard movement of the warp delivery means, a pair of connected members each of which is connected to one end of the flexible element, said members being normally locked in stationary position but movable concentrically with respect to the cylindrical friction surface, and means carried by one of said members to adjust the position of the other member, said members being movable from normal adjusted position relatively to each other to slacken the flexible member and thereafter movable about the center of the friction surface to move the flexible member as a whole, said means holding the members in normal relative position after said members are returned to their original relative position to tighten the flexible friction element, said members being movable toward their normal stationary position to give a reverse movement to the friction surface after being restored to normal relative position.

In testimony whereof I have hereunto affixed my signature.

WALTER H. WAKEFIELD.
